UNITED STATES PATENT OFFICE.

MENOTTI PELLEGRINO, OF NEW YORK, N. Y.

SPRING-WHEEL.

1,250,643.

Specification of Letters Patent. Patented Dec. 18, 1917.

Application filed August 4, 1917. Serial No. 184,443.

To all whom it may concern:

Be it known that I, MENOTTI PELLEGRINO, a subject of the King of Italy, residing at New York, in the county of New York and 5 State of New York, have invented certain new and useful Improvements in Spring-Wheels, of which the following is a specification.

The basic object of my invention is to 10 provide a novel construction of automobile wheel-rim as a substitute, possessing great durability, for the objectionably perishable and burstable and puncturable pneumatic tire now commonly employed.

15 Another object is to provide a wheel-rim, of peculiar construction, which may be adjusted properly on any wheel, and which is not subject to the expense of alteration.

Another object is to provide a construction 20 of the character noted which will, while dispensing with the use of a pneumatic rubber tire, preserve the quality of elasticity and ease in riding possessed by pneumatic rubber tires.

25 Another object is to provide a construction which will not be likely to get out of order, thus avoiding the necessity of labor and skill in making repairs.

Other objects, relating to matters of specific improvement, going to make up the 30 ultimate perfection of the entire device, will appear as the specification proceeds and the nature of the invention more fully appears.

With these objects in view, the invention 35 relates more particularly to a deformable outer rim, comprising independent, metallic rim-segments, in combination with spring-pressed, telescoping plungers; and resides in the peculiar construction, combination 40 and arrangement of parts thereof, as fully hereinafter described in the specification, pointed out in the claim, and illustrated in the drawing.

In the accompanying drawing, forming 45 part of my specification, I have illustrated a form of embodiment capable of carrying out the underlying principles of the invention; like reference characters denoting corresponding parts throughout the several 50 views. The several views of the drawing may be briefly described as follows:

Figure 1 is a view in side elevation partly in section of my wheel rim;

Fig. 2 is a fragmentary detail view, in top 55 plan, of the inner rim;

Fig. 3 is a section on the line 3—3, Fig. 1;

Fig. 4 is a detached detail view, in perspective, of one of the outer rim-segments; and

Fig. 5 is a transverse vertical sectional view, showing a slight modification, in respect to the disposition of the helical springs.

Referring, now, in detail to the drawing:

1 designates an inner rim, which, as shown, is an annulus provide with circumferential, marginal flanges 2, 2, having transverse slots 3 extending from the free edges thereof, for a purpose presently appearing; the rim also carrying a plurality of radial, tubular spokes or posts 4.

The deformable outer rim consists of a plurality of independent, movable rim-segments 5, alternate ones of which (or all of which) may be provided with marginal flanges 6, 6, for a purpose presently appearing.

Each of said rim-segments 5 is also provided at the longitudinal sides or edges with guide-flanges 7 bearing against the inner surface of the flanges 2, 2, and carrying lateral pintles 8 projecting into the slots 3, whereby the movable rim-segments 5 are properly guided in their movement, and whereby movement in the direction of the length thereof is prevented.

The rim-segments 5 are of a width to fit snugly between the flanges 2, 2 of the rim 1, so that sidewise movement of the rim-segments will be prevented.

Each rim-segment 5 carries a plurality (in this instance, six) of tubular members 9, of slightly greater diameter than the posts 4, whereby the members 9 telescope on the posts 4.

Disposed within each telescoping member 9 and its corresponding post 4 is a helical spring 10 (or said springs may be disposed so as to encircle said members and posts, as shown in Fig. 5).

A tough, flexible belt 11, constituting a tread, is disposed over the movable rim-segments 5, and is preferably of a material other than rubber, such as some appropriate textile material, which, while affording a durability incomparably superior to that of a rubber belt, will hold the rim segments 5 in position, and will bridge over any slight crack that there may be between any two adjacent rim-segments. Sidewise displacement of the belt is prevented by the flanges 110

6, 6 of the rim-segments 5, the belt being of a width to fit snugly between such flanges.

In the slight modification shown in Fig. 5, the only difference is that the springs 10' encircle the telescoping members and posts, instead of lying therewithin.

Having thus fully described my invention, the many advantages thereof will be apparent, especially to those skilled in the art to 10 which it pertains. While, for the purposes of the patent statutes, I have described with great particularity a concrete embodiment of my invention, it is to be understood that I am not limited to the precise physical embodiment, since variations, especially in detail, may be made, within the scope of the 15 appended claim, without departing from the scope and spirit of the invention.

Having thus fully described my invention,

what I claim as new and desire to secure by 20 Letters Patent of the United States is:

The combination, with an inner rim having integral, marginal flanges provided with transversely alined slots extending from the free edges thereof, of tubular posts carried by said rim, a deformable outer rim, comprising independent, movable rim-sections, each having, at its longitudinal edges, guide-flanges having integral projections disposed in said slots, cylindrical members carried by 25 said rim-sections and telescoping said posts, helical springs interposed between said rim-sections and said inner rim, and a tread comprising a flexible belt disposed over said rim-sections and holding them in position against 30 accidental removal.

In testimony whereof, I affix my signature.

MENOTTI PELLEGRINO.

Copies of this patent may be obtained for five cents each, by addressing the "Commissioner of Patents, Washington, D. C."
